SELF-CLEANING CONVEYER BUCKET

Jules T. Parisi, Chicago, Ill.

Application November 1, 1947, Serial No. 783,583

14 Claims. (Cl. 198—144)

1

The present invention relates to conveyor buckets and more particularly to a self-cleaning conveyor bucket.

Conveyor buckets of conventional construction for conveying granular material from one point to another by means of an endless conveyor belt, to which the buckets are attached, do not operate entirely satisfactorily where the material conveyed is moist or sticky because some of the material sticks to the bottom and side walls of the bucket when the bucket is tipped for dumping. This occurs, for example, when conventional buckets are used for conveying molding sand from one station to another because this sand ordinarily is mixed with a quantity of binding material such as molasses so that it is relatively sticky and viscous and will tend to stick on the bottom and side walls of a conveyor bucket as the bucket is tipped for dumping in passing over the head wheel of the system.

It is, therefore, a primary object of the invention to provide a new and improved conveyor bucket for use in conjunction with conveyor belt systems which incorporates a movable plate or cleaner for dislodging material on the bottom and side walls of the bucket when the bucket is carried to a predetermined dumping position by the conveyor belt, and for automatically returning this cleaning means to its original position as the bucket passes beyond the dumping position.

Another object of the invention is the provision of a new and improved self-cleaning conveyor bucket for use on conveyor belt systems in which the stripper or cleaner plate forms the back wall of the bucket and is pivotally movable with respect to the other walls of the bucket to dislodge material clinging thereto.

A further object of the invention is the provision of a new and improved self-cleaning conveyor bucket for use on conveyor belt systems in which the need for separate tripping mechanism to actuate the cleaner plate when the bucket reaches a predetermined dumping position is eliminated and the cleaner is nevertheless automatically actuated.

A still further object of the invention is the provision of a bucket of the foregoing character in which the bucket and cleaner are independently secured to the belt in such a manner that they assume a tangential position with respect to the head wheel when passing thereover, but out of phase with respect to each other to thus produce relative movement between the parts that results in the walls of the bucket being stripped or cleaned of material clinging thereto.

2

Another and further object of the invention is the provision of a self-cleaning bucket of the foregoing character in which the bucket and cleaner are independently secured to the belt by means cooperating with the belt to hold these parts in full load carrying position when the belt is moving linearly, and cooperating with the belt and head wheel to produce movement of the cleaner relative to the bucket sufficient to dislodge material clinging to the front, bottom and side walls thereof as the bucket assembly passes over the head wheel of the conveyor belt system.

Yet another object of the invention is the provision of a new and improved self-cleaning bucket for use on conveyor belt systems which is simple in construction so that it may readily be manufactured at relatively low cost but which nevertheless is sturdy and entirely satisfactory in operation and reduces wear on the conveyor belt with which the bucket is used.

These and other objects, advantages and capabilities of the invention will become apparent from the following description wherein reference is had to the accompanying drawings, in which:

Fig. 1 is a diagrammatic side elevational view of a conveyor belt system of the type in which the improved buckets of the present invention might be used;

Fig. 2 is a vertical sectional view on an enlarged scale of the head wheel or dumping end of the system shown in Figure 1;

Fig. 3 is a vertical transverse sectional view of the improved conveyor bucket of the present invention attached to a portion of a conveyor belt;

Fig. 4 is a sectional view partly broken away and taken on the line 4—4 of Fig. 3;

Fig. 5 is a front elevational view of a bucket constructed in accordance with the present invention secured to a conveyor belt;

Fig. 6 is a front elevational view on a reduced scale of a modified form of self-cleaning conveyor bucket;

Fig. 7 is an enlarged vertical transverse sectional view of the bucket shown in Figure 6 with a phantom showing of the movable back plate which constitutes the cleaner in extreme cleaning position;

Fig. 8 is a sectional view partly broken away, taken on the line 8—8 of Figure 7;

Fig. 9 is a perspective view on a reduced scale of a further modification of the invention; and

Fig. 10 is a vertical transverse sectional view

3 through a variation of the modified form of the invention which is illustrated in Fig. 9.

The improved conveyor bucket of the present invention, indicated generally by the numeral 10 in Figs. 3 to 5, has a rigid shell including front and side walls 12 and 14, respectively, and an open back adapted to be closed by a plate 16 secured for movement between the side walls of the bucket 10 so that it functions both as a back wall for the bucket and as a cleaner for stripping material from the side and front walls of the bucket. The side walls 14 of the bucket are of generally trapezium shape to provide straight back edges 18 which rest upon the belt to which the bucket shell is attached when the belt is traveling linearly, bottom edges 20 normal thereto, and leading edges 22 acutely inclined with respect to the back edges and to the front wall 12. This front wall extends between and connects the opposite side walls 14 and has its leading edge inclined outwardly so that it may function as a scoop for gathering a load of material into the bucket as the latter is moved by the belt through a stock pile while the trailing edge of this front wall curves inwardly along the bottom edge 20 as indicated at 24 to form a portion of the bottom of the bucket. A mounting bar or plate 26 for securing the bucket shell to a conveyor belt extends between and is welded to the back edges 18 of the side walls adjacent the upper ends thereof.

While the front and side walls of the bucket shell shown are of integral construction and the mounting plate 26 is a separate piece welded to the back edges of the side walls, it should be understood that the front and side walls may be made as separate parts welded together along their front edges. It should also be understood that a reinforcing wear plate (not shown) may be secured to the outside of the leading edge of the front wall 12.

The combined back wall and stripping cleaner plate 16 is formed from a flat rectangular metal plate turned outwardly at its lower end, as indicated at 28 in Fig. 3, so that the peripheral edge of this curved end 28 engages upon the peripheral edge of the lower or trailing end 24 of the front wall 12 to form, in effect, a continuation of this wall and thus complete the bottom of the bucket when the parts are in the position shown in Fig. 3.

The bucket shell is secured to a conveyor belt which is indicated at 30 by anchor means comprising a series of bolts 32 extending through openings disposed in aligned relation transversely of the belt and through corresponding openings in the mounting plate 26. These bolts have enlarged flat heads 34 which engage against the back side of the belt, as shown in Figs. 3 and 4, and threaded tips for receiving lock nuts 36. Lock washers 38 are preferably interposed between the nuts 36 and the plate 26 for locking the nuts in position when they are tightened upon the bolts.

In the same manner, and by means of anchoring bolts 40 similar to the bolts 32, the back or cleaner plate 16 is independently secured to the belt along a line in advance of the leading edge of the bucket shell and also in advance of the line along which the bucket shell is attached to the belt. It will be noted in Fig. 3 that a spacing bar 42 of the same thickness as the mounting plate 26 is interposed between the back or cleaner plate and the belt, and that the cleaner plate is provided with a series of apertures 44

axially aligned with the bucket bolts 32 and of sufficient diameter to receive the nuts 36 therein, thus permitting the cleaner plate to rest upon the mounting plate 26 when the cleaner plate is in the retracted position shown in Fig. 3 for carrying a maximum load in the bucket.

Preferably the bolts 32 and 40 securing the bucket shell and combined cleaner and back plate 16 to the belt are arranged in staggered relation, as shown, so that the belt will not be unduly weakened. The large flat heads on these bolts prevent the same from tearing through the belt, and engage upon the head wheel or roller of the conveyor belt system when a bucket assembly is passing thereover. The tension in the belt urges the bolts to a normal position with respect to the belt at all times so that the bucket shell and back plate are held in the maximum load carrying position shown in Fig. 3 when the belt is traveling linearly. However, when the bucket is passing over the head wheel the flat heads of the bolts 40 and 32 engaging upon the circular periphery of the head wheel cooperate with the tensioned belt to urge the bolts to a radially extending position with respect to the axis of the head wheel. Movement of the bolts 40 and 32 to this position causes the combined cleaner and the back plate 16 and bucket shell 10 to be moved to tangential position with respect to the head wheel and this position is maintained throughout the course of travel of the bucket over the head wheel. Since the plate 16 is secured in advance of the bucket shell 10, its securing bolts 40 will engage the head wheel in advance of the bolts 32 securing the bucket shell so that the back plate 16 will be moved to tangential position with respect to the head wheel of the system prior to the time that the bucket shell is moved to a like position; thus producing the relative movement between the parts, which dislodges material on the walls of the bucket shell.

In Figs. 1 and 2 is shown diagrammatically, by way of illustration, an endless conveyor belt system provided with a series of conveyor buckets of the type described above. Such a system may be installed with its loading end in a bin 46 or the like, in which a stock pile of the material to be moved is contained and the system includes an endless conveyor belt 30, a driving member 48 for the belt operatively connected to a suitable source of power 50, such as an electric motor. A head wheel 52 is disposed at the place where the material to be moved is to be dumped which is illustrated as a horizontal conveyor belt in Fig. 1, and all of these parts are suitably mounted so that the driving member 48 and head wheel 52 define the limits of a path or orbit over which the belt travels.

A series of buckets 10 of the self-cleaning type, above described, are secured to the belt, as described, at intervals sufficiently spaced so that only one bucket at a time is at the dumping position.

Referring to Fig. 2, it will be noted that the combined cleaner and back plate 16 of the buckets disposed along the portion of the belt which is moving linearly are in retracted position so that the bucket will carry a maximum load. This is true, both on the upside and the downside of the belt, as indicated at 10¹ and 10², as a result of the cooperative action between bolts 32 and 40 and the taut belt. The load in the buckets on the upside of the belt of course additionally insures

that the back plate 16 of these buckets will remain in maximum load carrying position.

When movement of the belt brings the heads of the back plate securing bolts 40 into engagement with the head wheel 52, these bolts assume a radial position with respect to the axis of the head wheel and exert a force on the combined cleaner and back plate 16, sufficient to cause it to move with respect to the bucket shell and assume a tangential position with respect to the head wheel, as indicated at 16¹ in Fig. 2. This movement of the back plate dislodges material on the bottom and side walls of the bucket as indicated, and is limited by engagement of the lower edge 28 of the back plate 16¹ with the inside of the front wall 12. As the belt moves further along the head wheel, the heads of the bucket securing bolts 32 engage the head wheel and the buckets 16 are moved to a tangential position with respect to the head wheel as shown at 16² in Fig. 2, but the bucket shell and back plate will be maintained in out of phase tangential position with respect to each other throughout their course of travel over the head wheel because of their spaced mounting.

This same action will occur as the belt moves a bucket assembly over the driver 48, but the weight of the material against the back plate 16, as the front wall scoops into the stock pile, will tend to limit this movement so that a full load will be taken on by the bucket, and moreover the bucket and back wall will again be urged to maximum load carrying position as the bucket moves off the driver so that any slight movement of the back wall which may have occurred during loading will tend to create an air pocket under the load in the bucket, thus facilitating emptying of the bucket as it passes over the head wheel. Furthermore, loading of the buckets will usually occur at a point where they have passed beyond the driver 48 so that the buckets will be in maximum load carrying position.

In Figs. 6-8 a modification of the invention is shown generally similar to the embodiment previously described in that the bucket shell 54 has trapezium shaped side walls 56 rigidly secured to an inclined front wall 58 and a portion of a bottom wall 60 which, as shown, is in the form of a separate plate welded to the bottom edges of the side walls and to the lower edge of the front wall. This portion of the bottom wall could of course be formed integrally with the front wall. The bucket shell has a mounting plate 62 welded to the back edges of the side walls 56 and the shell is secured to a belt 30 by means of bolts 64 upon which lock washers and nuts are engaged in a manner similar to the manner in which the bucket first described is secured. A reinforcing plate 66 may be welded to the leading edges of the front and side walls, as shown, to reduce wear on these edges.

Referring to Fig. 7, it will be seen that the open back of the bucket shell is closed by a cleaner plate 68 which also forms the back wall of the bucket. This plate is secured to the belt 30 in advance of the place of securement of the bucket shell by means of bolts 70, and is spaced from the belt by means of a spacing plate 72. Plate 68 inclines outwardly from a point adjacent the top edge of the mounting plate 62 so that its back side barely engages the ends of bolts 64 when the bucket shell and plate are in the maximum load carrying position, shown in Fig. 7. Thus the need for the openings 44 of the first modification is eliminated.

In addition to this modification in structure,

it will be noted that the lower end of the plate 68 is not curved and that it is secured sufficiently in advance of the place of securement of the bucket shell so that it may completely sweep the bucket shell, as shown in phantom in Figure 7.

This form of bucket is designed to obviate the difficulty that may arise in the use of the buckets 16 first described which have openings 44 in the back plate 16 since the material being conveyed tends to clog in these openings and between the back plate and the mounting plate 26. However, this is not a serious disadvantage because the material can be quickly dislodged by running the conveyor belt empty for a short period of time.

Although I have shown and described the combined cleaning and back plate as being secured to a conveyor belt in advance of the bucket shell, in order that the two parts will move relative to each other as they are moved over the head wheel of the conveyor belt system, it will be apparent that relative movement between these parts can also be effected by securing the bucket in advance of the back wall.

The independent mounting of the bucket shell and back plate herein described has certain additional advantages, the most important of which is that it reduces wear on the belt as compared with the wear produced by the mounting of a conventional bucket. This is due to the fact that the two or more rows of securing bolts, or the like, for conventional buckets are spaced a fixed distance from each other so that there is no play between them and therefore the belt cannot conform as closely to the contour of the head wheel when it carries a bucket over the same as it can with the independent mounting described above. As a result conventional buckets place a strain on the belt that cannot arise with the independent mounting of the bucket shell and back plate herein disclosed.

This independent mounting also allows for control of the sweeping or cleaning movement of the combined cleaner and back plate because the extent of this movement can be altered by increasing or decreasing the space between the bucket securing bolts and the back plate securing bolts. Furthermore since the bucket assembly is made in two parts rather than one, replacement is less expensive if one part wears out before another.

In Fig. 9 there is shown a further modification of the invention which is adaptable for use with conventional conveyor buckets, one of which is indicated at 74. This bucket is secured to the belt 30 in a conventional manner by means of two rows of bolts indicated at 76.

A cleaner which may be either a flat rectangular plate or an open rectangular framelike member, as indicated at 78, is secured at its upper end to the belt 30. When the cleaner is in the form of an open frame, a crosspiece 80, connected to the upper ends of the sides of this frame, as by welding, is provided for securing the cleaner to the belt by means of bolts similar to the bolts 32 or 40 previously mentioned, and a spacer plate may be interposed between the crosspiece 80 and the belt for holding the cleaner in the plane of the back wall of the bucket.

It will be apparent that this cleaner functions in the same manner as the cleaner previously described. It should also be noted that this cleaner is secured independently of the bucket which it cleans and in advance thereof so that relative movement between the cleaner and bucket is produced in the manner described for the pre-

vious embodiments of the invention. This form of the invention has another advantage where it is to be used on a conveyor belt system in which the buckets are relatively closely spaced. In such a system each cleaner can be secured to the belt under the bucket immediately in advance thereof so that one of the rows of bolts 76 securing the buckets may also serve to secure a cleaner to the belt. Thus, in Fig. 10, there is shown a construction identical to that of Fig. 9, except the crosspiece 80 is secured to the belt 30 by the bottom row of bolts 76 of the leading bucket 14.

While I have shown and described preferred embodiments of my invention, it will be apparent that numerous variations and modifications thereof may be made without departing from the underlying principles of the invention. I, therefore, desire by the following claims to include within the scope of the invention all such variations and modifications by which substantially the results of my invention may be obtained through the use of substantially the same or equivalent means.

I claim:

1. A bucket for a conveyor system including a conveyor belt and a head wheel over which the belt passes, comprising a shell having opposite end walls and a bottom and a front wall extending between said end walls and cooperating therewith to define a bucket, a cleaner for said bucket including a part extending into said bucket from the forward end thereof, said cleaner having a substantially flat portion at its forward end extending transversely of the belt in substantially parallel relation thereto, and means independently to secure the bucket and cleaner to the belt including bolts having enlarged heads to engage the back side of the belt and cooperating with the cylindrical periphery of the head wheel when the bucket passes over the same to cause said bucket and cleaner to assume a tangential position relative to the head wheel when the bucket is moving over the same, said bolts securing said bucket and the bolts securing said cleaner being disposed in spaced relation longitudinally of the belt so that one of said parts is rocked relatively to tangential position before the other for causing the cleaner to dislodge material in the bucket.

2. A self-cleaning conveyor bucket as defined in claim 1, wherein the opposite end, bottom and front walls define a bucket open at its leading end only and wherein the cleaner comprises a generally U-shaped heavy wire or bar stock frame extending into said bucket shell with the sides of said frame in close proximity to the end walls of said bucket and the free end of said frame in close proximity to the rear end of said bucket, said end of the frame closely following the contour of the said front wall when said cleaner and bucket are rocked relatively.

3. A self-cleaning conveyor bucket as defined in claim 1, wherein the cleaner and the front wall of said bucket include cooperating portions adapted to be brought into abutting engagement upon relative movement of said bucket and cleaner to limit such relative movement.

4. A bucket for a conveyor system including a conveyor belt and a head wheel over which the belt passes, comprising a shell having opposite end walls with bottom edges, a bottom wall in the plane of said bottom edges and a front wall, said bottom and front walls extending between said end walls and cooperating therewith to define a bucket having an open back, a cleaner for said bucket including a part extending into said

bucket for closing said open back, said cleaner having a substantially flat portion at its forward end extending transversely of the belt in substantially parallel relation thereto, and means independently to secure the bucket and cleaner to the belt including bolts having enlarged heads to engage the back side of the belt and cooperating with the cylindrical periphery of the head wheel when the bucket passes over the same to cause said bucket and cleaner to assume a tangential position relative to the head wheel when the bucket is moving over the same, said bolts securing said bucket and the bolts securing said cleaner being disposed in spaced relation longitudinally of the belt so that one of said parts is rocked relatively to tangential position before the other for causing the cleaner to dislodge material in the bucket.

5. In a conveyor system including a head wheel having a cylindrical periphery over which a conveyor belt passes, in combination, a conveyor bucket including substantially flat back wall structure, a series of bolts disposed in aligned relation transversely of the belt and extending through said belt and back wall structure to secure said bucket to said belt, a cleaner for said bucket including a substantially flat portion to extend transversely of said belt in substantially parallel relation thereto, and a series of bolts extending through said belt and the said flat portion of the cleaner and disposed in aligned relation transversely of the belt for securing the cleaner to the belt, said bolts securing said bucket and cleaner to said belt having enlarged flat heads engaging the back side of the belt and cooperating with the cylindrical periphery of said head wheel when the bucket and cleaner are moved to a predetermined position relative to the head wheel by movement of the belt to tip said cleaner and bucket relative to the belt, and said two series of bolts being disposed in spaced relation longitudinally of the belt so that one of said parts is tipped before the other.

6. A self-cleaning conveyor bucket for use in conveyor belt systems or the like having a head wheel over which the belt moves comprising a bucket shell having rigid front, bottom and side walls and an open back, means rockably to anchor the back of the said bucket to said belt, a back plate within said bucket shell to close the open back thereof, means to anchor said back plate to said belt for rocking movement relative to the bucket, said anchor means for the bucket and back plate including a part fixed relative to the belt and bucket cooperating with the belt to hold the bucket and back plate in maximum load carrying position when the belt is moving linearly and another part on the back side of said belt conformed to cooperate with the belt and head wheel to rock said bucket and cleaner relatively to another position for dislodging material in the bucket when the latter is moved to a predetermined position relative to the head wheel by movement of the belt.

7. In a conveyor belt system which includes a head wheel over which a conveyor belt passes, in combination, a plurality of conveyor buckets of duplicate construction secured to said belt in equally spaced relation longitudinally thereof, each of said buckets comprising a shell having end walls, a rear wall and front and bottom wall structure extending between said end walls and cooperating therewith to define a bucket, a cleaner for each bucket having a flat forward end extending transversely of the belt substantially

parallel thereto and a trailing part adapted to extend into said shell, anchor means to secure each of said cleaners and shells to said belt with the rear wall of said shell resting on the flat forward end of the cleaner and the trailing end of the cleaner extending into the shell immediately following the shell with which it is secured including a plurality of bolts disposed transversely of said belt and extending through the latter and said rear wall of the shell and flat forward end of the cleaner, said bolts having relatively large flat heads to engage the back side of said belt and to cooperate with the cylindrical periphery of the head wheel when the buckets pass over the same for causing said buckets and cleaners to assume a tangential position relative to the head wheel when they move over the same whereby the material in each bucket is loosened by the cleaner secured to the bucket leading it as the latter bucket starts to ride over the head wheel.

8. A bucket for a conveyor system including a conveyor belt and a wheel over which the belt passes, the bucket being attached to the belt and adapted to pick up material therein and discharge said material when that portion of the belt to which same is attached is passing over the wheel, said bucket comprising end walls and a bottom and a front wall defining the same, a cleaner for the bucket including a part extending into the bucket at the rear thereof and having a relatively stiff cross-member rigidly supporting said part and attached transversely of the belt independently of the bucket, said bucket being secured to said belt in spaced relation longitudinally thereof relative to the said stiff cross member, fastening devices for said cross member and bucket extending through said belt and clamping same to the belt and including bearing areas on the back side of the belt adapted to engage and cooperate with the cylindrical periphery of the wheel causing the cleaner and the bucket to assume circumferentially spaced tangential positions one after the other when the belt is passing over the wheel whereby to rock the cleaner and bucket one relative to the other for dislodging said material from the bucket.

9. A bucket for a conveyor system including a conveyor belt and a wheel over which the belt passes, the bucket being attached to the belt and adapted to pick up material therein and discharge said material when that portion of the belt to which same is attached is passing over the wheel, said bucket comprising a shell having an open back engaged against the belt and having a forward scooping edge for directing material into the shell, a cleaner member for the bucket including a plate-like part extending into the shell and of substantially the same width as the inside of the shell arranged to cover said open back thereof, the cleaner member being secured to said belt and pivotally movable within the shell relative thereto between the back and front thereof, the bucket and cleaner member being secured to the belt in spaced longitudinal relationship one to the other, fastening devices for said cleaner member and bucket extending through the said belt and clamping the same to said belt and including bearing areas on the back side of the belt adapted to engage and cooperate with the cylindrical periphery of the wheel causing the cleaner member and bucket to assume circumferentially spaced tangential positions one

after the other when the belt is passing over the wheel whereby to rock the cleaner member and one relative to the other for dislodging said material from the bucket.

5 10. A bucket construction as described in claim 9 in which the said open back of the shell has a rigid plate extending across the same, and the said fastening devices extend through the said plate.

10 11. A bucket construction as described in claim 10 in which the fastening devices have bolt heads on the said plate, and the plate-like part of the cleaner member extends into said shell and has a bend therein directed away from said rigid plate to clear the said bolt heads.

15 12. A bucket construction as described in claim 10 in which the fastening devices have bolt heads on the said plate, and the plate-like part of the cleaner member extends into the shell and overlies the said plate, and has perforations therein aligned with the bolt heads to permit the heads to enter therein and enable the said plate and plate-like part intimately to engage.

12 13. In combination with a conveyor belt passing over a head wheel, a self-cleaning bucket comprising a scoop shell anchored to said belt substantially along a line transverse of the belt so that the belt may bend relative to the shell ahead of and behind the line, a cleaning member

20 30 having one end similarly anchored to the belt, albeit along a transverse line spaced from the first-mentioned line and having a scraping free end disposed within the shell and capable of rocking relative thereto to disengage material from the interior thereof, the cleaning member and the shell both having parts rigidly connected respectively therewith and extending through said belt at the respective transverse lines and presenting planar surfaces on the backside of the belt

35 40 to the periphery of the wheel whereby the cleaning member and shell will be forced to assume positions tangential to the belt one after the other as the belt passes over the wheel, thereby rocking one relative to the other to dislodge material in the shell.

45 14. A self-cleaning conveyor bucket for use in conveyor belt systems or the like having a head wheel over which the belt moves comprising a bucket shell having a rigid front, bottom and side walls, means rockably to anchor said bucket shell to said belt including a rigid member on the front of the belt and fixed relative to said belt and bucket cooperating with the belt to hold the bucket in maximum load carrying position when

50 55 the belt is moved linearly and second rigid member on the back of the belt, connected to the first rigid member and conformed to cooperate with the periphery of the head wheel to rock the bucket relative to the belt as the bucket passes over the head wheel, a cleaner within the bucket shell normally at the back thereof while the bucket is moving linearly and means to anchor the cleaner to the belt independent of and for

60 65 rocking movement relative to the bucket including a third rigid member on the front of the belt and fixed relative thereto linearly spaced from said first rigid member and having a fourth rigid member on the back of the belt connected thereto and also conformed to cooperate with the periphery of the head wheel to rock the cleaner relative to the belt, said cleaner and belt rocking relative to one another during passage over the head wheel by virtue of the linear spacing between the first and third rigid members, whereby

70 75

11

the cleaner will move from the back to the front of the bucket to dislodge material in said bucket.
